[57] CLAIM

The ornamental design for a folding bar table, as shown.

DESCRIPTION

FIG. 1 is a perspective view showing the table of my
design in an open position;

FIG. 2 is a right side elevational view of the table; the
left side view being the mirror image thereof;

FIG. 3 is a rear elevational view thereof;

FIG. 4 is a top view of the table in a folded position;

FIG. 5 is a left side view of the table in a folded position;
the right side being the mirror image thereof;

FIG. 6 is a front view of the table in a folded position;
and

FIG. 7 is a rear view of the table thereof in a folded
position.
